UNITED STATES PATENT OFFICE.

MORRIS STEINBERG, OF DETROIT, MICHIGAN.

GAME DEVICE.

Application filed June 30, 1924. Serial No. 723,401.

To all whom it may concern:

Be it known that I, MORRIS STEINBERG, a citizen of the United States, and a resident of Detroit, in the county of Wayne and 5 State of Michigan, have invented a new and useful Game Device, of which the following is a specification.

A principal object of my invention is to provide a game device particularly adapted 10 for the playing of the game of checkers or draughts.

Another important object of the invention is to provide a game device used in determining the opening moves in the game 15 of checkers.

Another important object of the invention is to provide a new means of characterizing the openings of the game of checkers.

Still further objects of my invention will 20 be apparent during the course of the following description.

In the drawing, which forms a part of this specification and in which only a preferred form of my invention is shown,

25 Figure 1 is a plan view of my device, and Fig. 2 is a plan view of a checker board, the playing squares being numbered according to the standard notations.

Referring in detail to the drawings, in 30 which like characters of reference are employed to designate like parts throughout the same, the numeral 2 is a board having a central hole or bore 3. A pointer or arrow 4 is revoluble on a spindle 5 positioned 35 in the bore 3. A push of the finger upon the ball 6 of the arrow 4 or else upon the spear end 7 of the pointer 4 will send the pointer spinning in either a counter clockwise or clockwise direction.

40 Those skilled in the playing of the game of checkers know that in matches or contests the first two moves in checkers were balloted for or determined heretofore in a crude and inefficient way. My device determines the first two moves in the playing 45 of the game of checkers in a simple, inexpensive and efficient manner.

The board or plate on which the pointer 40 revolves, is divided into seven equal parts 50 A, B, C, D, E, F, G. Around the periphery of these seven parts A to G, are a number of radial lines marking each of the seven parts into seven subdivisions.

55 The seven major parts and forty-nine segments are marked in various ways, as will now be explained. In the playing of the

game of checkers, according to the rules and customs of experts in match play, etc., it has been found, after years of experience, that the first two moves should be predetermined or arranged in advance.

The twelve blackmen or pieces, numeral 8, are position on squares 1 to 12 inclusive, while the white men or pieces designated as 9 are placed on squares 21 to 32 inclusive, as shown in Fig. 2. Black moves first and it is obvious that it has seven first moves 9—13, I call A, 9—14 B, 10—14 C, 10—15 D, 11—15 E, 11—16 F, 12—16 G. No matter which one of these moves is made by 70 black, white has seven moves at its disposal. That is, 21—17, which I call 1, 22—17 2, 22—18 3, 23—18 4, 23—19 5, 24—19 6, 24—20 7.

The selection of the opening has heretofore been determined by crude devices, such as putting pieces of paper into a hat and drawing therefrom, throwing dice, etc. I am the first to invent a device for the purpose of determining the opening moves. 80

This device will same time and is inexpensive to manufacture and is simple to operate.

The opening moves or playing under a two move restriction, is determined by 85 either of the two players spinning the pointer or arrow 4. Where the pointer stops, that opening is played. For instance, Fig. 1 shows the arrow to be over A—3 meaning that black must play the move 9—13 and white's reply is 22—18. After 90 these moves are played of course, the moves are made in the usual manner until the game is concluded. My device may also be called a balloting determinator.

For the sake of fairness, after this game 95 is over, the players play another game wherein the colors are reversed and they play this same opening.

All of these possible openings have heretofore had a name usually many of Scotch 100 origin, such as Ayrshire Lassie, Psialey, Dundee, etc. The names of these openings have been found difficult to remember.

Since the adoption of my device, the openings have been distinguished as shown herein, such as G—1, A—7, B—5, etc., instead of these cumbersome, old-fashioned and foreign names. Likewise a variation of an opening may be named and classified by 105 another letter such as E 5 f.

110 It might be mentioned, at this time, that if the pointer swings to what would be B—1

or C—1, it is not counted and the pointer is spun to another position. It is obvious to those skilled in the art, that B—1, which would be black's move 9—14, and white's 5 counter reply 21—17, would lose a man. Black would simply continue 14 to 21 winning a piece and the game. The same result would occur if black played 10—14 and white replied 21—17. Therefore, on my device 10 I have marked B—1 and C—1 as "Loss". Deducting these two barred openings from the total of forty-nine possible first moves, gives a remainder of forty-seven playable openings in the game of checkers.

It must be understood that only a preferred form of my invention is herein shown and described and that any departure from the same, such as in shape, size or arrange-

ment of parts may be resorted to without departing from the spirit of the invention or the scope of the subjoined claims.

Having thus described my invention what I claim as new is:

1. A game device used in connection with the game of checkers comprising a board, markings on the board indicating all possible first moves of said game, a pointer revolvably mounted on said board whereby upon the pointer being revolved it will indicate the first move in the game.

2. A balloting determinator used in the game of checkers comprising markings on said determinator to indicate all possible first moves of each player and means on said determinator to point and name any particular opening.

MORRIS STEINBERG.
